UNITED STATES PATENT OFFICE.

OTTO F. STUPPAN, OF MILWAUKEE, WISCONSIN, ASSIGNOR TO COLUMBIA GRAPHOPHONE MANUFACTURING COMPANY, OF BRIDGEPORT, CONNECTICUT, A CORPORATION OF DELAWARE.

AUTOMATIC STOP FOR SOUND-REPRODUCING MACHINES.

Application filed October 12, 1921. Serial No. 507,268.

To all whom it may concern:

Be it known that I, OTTO F. STUPPAN, a citizen of the United States, and resident of Milwaukee, in the county of Milwaukee and 5 State of Wisconsin, have invented new and useful Improvements in Automatic Stops for Sound-Reproducing Machines, of which the following is a description, reference being had to the accompanying drawings, 10 which are a part of this specification.

The invention relates to automatic stops for sound reproducing machines.

The object of the invention is to provide stop mechanism of a novel character for automatically stopping the drive of the machine when the playing of the record has been completed without the necessity of setting the stop mechanism.

A further object of the invention is to 20 provide a stop mechanism for sound reproducing machines which is automatically operated by a reverse movement of the tone-arm on a completion of its inward travel on the record.

25 The invention further consists in the several features hereinafter set forth and more particularly defined by claims at the conclusion hereof.

In the drawings: Fig. 1 is a plan view of 30 a device embodying the invention; Fig. 2 is a side elevation view thereof.

Figure 3 is a plan view of the device, the full lines showing the position of the parts when the tone-arm is swung to an extreme 35 position to release the brake, and the dotted lines showing the position of the parts when the brake is applied; and

Figure 4 is a detail view in plan of parts shown in Figure 3, the coil spring being 40 omitted for the sake of clearness.

In the drawings the numeral 3 designates a brake member or lever pivoted on a pin 4 carried by a base plate 5 and engageable with the flanged edge of the turntable 6 to 45 stop the operation of the machine, the brake being provided with a handle 7 for setting it.

A latch 8 is pivotally mounted on a pin 9 carried by the plate 5 and is held in engagement with a notch 10 in the brake lever 3 by means of a spring 11 secured at one end to a projection 12 on the brake lever and at the other to an arm 13 on the latch. When 50 the latch 8 engages the lever, said lever will

be held in inoperative position until the latch is released.

For releasing the latch I provide means which is inoperative while the tone-arm 14 swings inwardly as the stylus 15 travels inwardly in the playing groove of the record 60 16, but which acts upon said latch as soon as the stylus is given a reverse motion upon the completion of the rendition of the record. For this purpose I provide a lever 17 which is mounted on the pin 9 and operatively connected with the latch 8 by means of friction disks 18. This lever is connected to move with the tone-arm 14 by a pin 19 secured by a clamp 20 to said arm and engaging in a slot 21 in said lever. When the 70 playing of the record is completed, I provide an eccentric groove 22 in the record which when travelled over by the stylus 15 causes an outward or reverse movement of the tone-arm 14 from its inward playing 75 movement.

With this construction the frictional connection between the lever 17 and the latch 8 permits relative movement between said parts when the tone-arm 14 moves inwardly 80 while the record is being played and such movement of the lever 17 also acts in conjunction with the spring 11 to hold the latch 8 against the brake lever. When the playing of the record is completed the outward 85 swing of the tone-arm by the action of the eccentric groove 22 causes the lever 17 to oppose the spring 11 and release the latch 8 from the brake lever, this movement being very slight but sufficient to unhook the latch 90 so that the spring 11 may then throw or swing the brake lever 3 into engagement with the turntable to stop its rotation.

After the turn-table has been stopped in the manner just described, the brake may 95 be released and the turn-table again permitted to rotate, by swinging the tone-arm into the extreme position shown in full lines in Figure 3 of the drawings. In this position of the tone-arm, the latch 8 is swung 100 on its pivot 9 a distance sufficient to move the spring 11 from one side of the pivot 4 to the other side thereof, and thus cause the spring to rock the brake member on its pivot in a direction away from the flanged 105 edge of the turn-table. As the tone-arm is moved inwardly from the full line position of Figure 3 towards the outer edge of the

record, the latch 8 will be swung upwardly into a position to engage with the notch 10 in the brake lever 3. Such engagement between the latch and brake lever, of course, holds the latter in inoperative position until the tone-arm is again given a backward movement.

From the foregoing description it will be noted that it is not necessary to provide any special setting for the release of the latch 8 on the completion of the record, because this release is automatically effected by the reverse movement of the tone-arm, due to the groove in the record. This eccentric groove is nothing but a circular groove cut in the record off center so that at one point it meets the last groove of the record and may be easily formed in the usual records without any special skill on the operator's part.

I desire it to be understood that this invention is not to be limited to any specific form or arrangement of parts except in so far as such limitations are specified in the claims.

What I claim as my invention is:

1. In a sound reproducing machine, the combination of a record with an eccentric terminal groove producing a backward swing of the tone-arm when the playing of the record has ceased, brake mechanism, including a member, a detent therefor, and a spring connecting the brake member and detent, and adapted to actuate them to braking and retaining positions, respectively, and means operating on said brake mechanism during the backward swing of the tone-arm to stop the operation of the machine.

40 2. In a sound reproducing machine, the combination with the tone-arm, of a brake member, a latch pivoted for holding said member in inoperative position, means movable with said tone-arm and pivotally mounted to rotate about the pivotal axis of the latch and means exerting axial frictional pressure between the latch, and means whereby the latch is released upon a backward swing of the tone-arm, and means causing a backward swing of the tone-arm when the playing of the record is completed.

3. In a sound reproducing machine, the combination, with the tripping lever of the brake mechanism, the record, the stylus and the tone-arm, of means moving with the tone-arm and having a frictional pivot connection with said lever to operate the same on a backward swing of the tone arm, and means on the record engaged by the stylus when the playing of the record is completed to produce the backward swing of the tone-arm.

4. In a sound reproducing machine, the combination, with the tripping lever of the brake mechanism, the record, the stylus and

the tone-arm, of a member moving with the tone-arm, a spring washer establishing frictional connection between the lever and said member, whereby the lever is operated on a backward swing of the tone-arm, and means on the record engaged by the stylus when the playing of the record is completed to produce the backward swing of the tone-arm.

5. In combination, a brake, a detent, a single spring adapted to move both the brake and the detent to effective position, and means including the said spring for moving the brake to ineffective position.

6. In combination, a traveling member, a rotating member, a brake for the latter, a pivoted detent, an operating arm having a pin and slot connection with the traveling member and mounted coaxial with the detent and having frictional connection therewith.

7. In a stop mechanism, a brake member, a detent for retaining the brake member in non-braking position, and a single spring adapted to yieldingly retain the brake member in braking and to move the brake member to non-braking position.

8. In a stop mechanism, a rotating element and a traveling element, and means whereby said traveling element is given a reverse movement at a predetermined point in its travel, a pair of coaxially mounted members, one adapted to be moved by said traveling element, and the other adapted to actuate the stop mechanism to stopping position upon movement in one direction, and means exerting pressure coaxially of said member to establish a frictional connection between them, whereby movement of the traveling element in reverse direction moves said actuating member in stop-actuating direction.

9. In a stop mechanism, a rotating element and a traveling element, and means whereby said traveling element is given a reverse movement at a predetermined point in its travel, a pivoted brake member, a pivoted detent adapted to be moved in one direction to release said brake member, and a member having frictional connection with said detent and operatively connected to said traveling element, whereby movement of said traveling element in reverse direction operates said detent to release the brake member.

10. In combination, a traveling element having forward and backward movements, a rotating element, and a brake for the rotating element, and means operative to apply the brake upon a backward movement of a predetermined extent and operative to release the brake upon a backward movement in excess of the said predetermined extent.

11. In combination, a traveling element

- having forward and backward movements, a rotating element, and a brake for the rotating element, and means for applying the brake operable automatically only when the traveling element is given a predetermined, backward movement.
12. In combination, a turn-table for supporting a record, a tone-arm advanced over the turn-table by the rotation thereof, a brake for causing the rotation of the turn-table to cease, and brake-applying means automatically operative only as an incident to a predetermined backward movement of the tone-arm under the influence of the record.
13. In combination, a turn-table for supporting a record, a tone-arm advanced over the turn-table by the rotation thereof, a brake for causing the rotation of the turn-table to cease, and brake-applying means automatically operative only as an incident to a predetermined backward movement of the tone-arm under the influence of the record, the said means itself causing the release of the brake upon a backward movement of the tone-arm toward the edge of the record in excess to such predetermined backward movement.
14. In combination, a turn-table for supporting a record, a tone-arm advanced over the turn-table by the rotation thereof, a brake for causing the rotation of the turn-
- table to cease, and brake-applying means automatically operative only as an incident to a predetermined backward movement of the tone-arm under the influence of the record, the said means itself causing the release of the brake upon a backward movement of the tone-arm toward the edge of the record and being adapted to cause the brake member to be yieldingly urged to effective position when the tone-arm is advanced toward the playing position.
15. In combination, a brake lever, a spring having one end connected to the brake lever, a lever connected to the other end of the spring, and means for shifting the last-named lever whereby the spring is caused to yieldingly urge the brake lever toward operative position, or to yieldingly retain the brake lever in inoperative position.
16. In combination, a brake lever, a controlling lever for the brake lever, a spring connecting the two named members and normally lying in a line at one side of the pivot point of the lever, and means for shifting the position of the brake-controlling lever, to cause the spring to cross the pivot point of the brake lever and to retain the brake lever in ineffective position.

In testimony whereof I affix my signature.

OTTO F. STUPPAN.
